SIDE FRAME

Robert B. Cottrell, Chicago, Ill., assignor to American Steel Foundries, Chicago, Ill., a corporation of New Jersey

Application August 20, 1930, Serial No. 476,460

26 Claims. (Cl. 105—205)

This invention pertains to side frames.

It is an object of this invention to provide a truck side frame so designed as to meet all test requirements for A. R. A. side frames of this type.

A further object of the invention is to provide a Vulcan side frame adapted for use with the suitable journal box heretofore used or any suitable journal box, yet one which fulfills all test requirements of deflection and set.

Another object of the invention is to provide a side frame construction of the Vulcan type which fulfills all requirements of manufacture and service.

With these and various other objects in view, the invention may consist of certain novel features of construction and operation as will be more fully described and particularly pointed out in the specification, drawing and claims appended hereto.

In the drawing, which illustrates an embodiment of the device and wherein like reference characters are used to designate like parts—

Figure 1 is a top plan view of substantially one-half of a Vulcan type side frame embodying the invention;

Figure 2 is a side elevation of the side frame construction illustrated in Figure 1;

Figure 3 is a bottom plan view of the side frame construction illustrated in Figure 1; and

Figure 4 is an end elevation of the side frame construction illustrated in Figure 1.

The side frame construction is shown as of the so-called Vulcan type and includes a tension member 10, a compression member 12 merging adjacent the ends thereof into an end portion 14 disposed above the integral spaced jaws 16 adapted to receive the suitable journal box associated with this construction, a securing lug 18 being provided between said jaws for receiving a securing bolt or other fastening means for said journal box. The tension member includes the spring seat portion 20 and the upwardly extending portion 22, said portion merging with the downwardly extending portion 24 of the compression member 12, said portion 24 merging into the end portion 14 and into a central portion 26, the tension and compression members 10 and 12 being integrally connected by means of the spaced column guides 28.

The portions 22 and 24 of each of the tension and compression members are substantially U-shaped in section and face each other in way of the reinforcing flange 30 integrally formed with the tension and compression member and

each of the column guides. The central portion 26 of the compression member between the spaced column guides is substantially parallel sided, the portion 22 converging toward the end portion 14, the member 24 being of substantially greater transverse cross-section than the cross section of the member 22 as indicated in Figure 4. The end portion 14 comprises the upper and lower parts 32 and 38 which are formed with the spaced walls 34 and 37, respectively, connected together by the walls 36 which converge downwardly from walls 34 toward each other over the jaws 16 to merge with the walls 37. It will be noticed that the parts 32 and 38 are formed as substantially continuations of the compression and tension members, respectively. The walls 37 of lower part 38 are spaced apart substantially the same distance as the walls of the tension member 22 and are connected by a web 39 which is a continuation of web 44 thereof. The upper part 32 has side walls 34 connected by a top web 41 formed as a continuation of the web of the compression member 24 and these walls to a point 43 are spaced apart at substantially the same distance as the walls of this compression member. From the point 43 outwardly to the end of this part the walls 34 converge toward each other.

Cross ribs 40 and 42 are provided in the member 24 of the compression member adjacent the end of the aperture formed by the side portions which form a brace for the side walls, preventing collapse of these side walls which in effect are warped, and it will be noticed that the bottom or connecting wall of the member 22 is increased in thickness toward the upper portion thereof as at 44 to provide increased strength adjacent the inner corner of the journal box adjacent the inner of the jaws 16.

With this construction it will be seen that a very advantageous, rigid and strong construction is provided and it is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a side frame, the combination of a beam member having openings adjacent the ends thereof, said ends being adapted to be provided with journal boxes, said ends having upper and lower spaced side walls, said upper spaced walls 55.

being spaced apart a greater distance than said lower spaced walls, and walls connecting said upper and lower spaced side walls, said walls originating adjacent said openings and extending outwardly therefrom.

5 2. In a side frame, the combination of a beam member having openings adjacent the ends thereof, said ends being adapted to be provided with journal boxes, said ends having upper and lower parts, said upper part having a cross-sectional area for a portion of its length greater than the cross-sectional area of the lower part and a smaller cross-sectional area for the remaining portion of its length, and connecting parts between said first-named parts originating adjacent said openings and extending outwardly therefrom.

10 3. In a side frame, the combination of a beam member having openings adjacent the ends thereof, said ends being adapted to be provided with journal boxes, said ends having upper and lower parts provided with spaced walls, the walls of said upper part being spaced for a portion of its length at a greater distance than the walls of said lower part, said walls being spaced apart at a less distance for the remaining portion of the length thereof, and connecting walls between said parts originating adjacent said openings and extending outwardly therefrom.

15 4. In a side frame, the combination of tension and compression members terminating in an integral journal box receiving portion, the lower part of said portion adjacent said tension member including spaced walls, the upper part of said portion being formed as a substantial continuation of said compression member, and spaced walls connecting said upper and lower parts, said walls originating adjacent the intersection of said members and converging from said upper part to merge with the walls of said lower part.

20 5. In a side frame, the combination of tension and compression members terminating in an integral journal box receiving portion, said portion being provided with upper and lower parts formed as substantial continuations of said members, said lower part being provided with spaced walls and a connecting web, and spaced walls connecting said upper and lower parts, said walls originating adjacent the intersection of said members and converging from said upper part to merge with the walls of said lower part.

25 6. In a side frame, the combination of tension and compression members terminating in an integral journal box receiving portion, said portion being provided with upper and lower parts formed as substantial continuations of said members, said lower part and tension member being provided with spaced walls and a connecting web, said web being of integral and continuous construction and being of tapering thickness, the greatest thickness being adjacent one corner of the associated journal box, and spaced walls connecting said upper and lower parts, said walls originating adjacent the intersection of said members and converging from said upper part to merge with the walls of said lower part.

30 7. In a side frame, the combination of tension and compression members terminating in an integral journal box receiving portion, said portion being provided with upper and lower parts formed as substantial continuations of said members, said parts and members being provided with spaced walls and connecting webs, and spaced walls connecting the walls of said upper and lower parts, said walls originating adjacent the intersection

of said members and converging from the walls of said upper part to merge with the walls of said lower part.

35 8. In a side frame, the combination of tension and compression members terminating in an integral journal box receiving portion, said portion being provided with upper and lower parts formed as substantial continuations of said members, said compression member and a portion of said upper part having a cross-sectional area greater than the cross-sectional area of said lower part and said part having a smaller cross-sectional area for the remaining portion of its length, said lower part being provided with spaced walls, and spaced walls connecting said upper and lower parts, said walls originating adjacent the intersection of said members and converging from said upper part to merge with the walls of said lower part.

40 9. In a side frame, the combination of tension and compression members terminating in an integral journal box receiving portion, said portion being provided with upper and lower parts formed as substantial continuations of said members, said parts and said compression member being provided with spaced walls, the walls of said compression member and the walls for a portion of the length of said upper part being spaced apart at a greater distance than the walls of said lower part, and spaced walls connecting the walls of said upper and lower parts, said walls originating adjacent the intersection of said members and converging from the walls of said upper part to merge with the walls of said lower part.

45 10. In a side frame, the combination of tension and compression members terminating in an integral journal box receiving portion, said portion being provided with upper and lower parts formed as substantial continuations of said members, said parts and said compression member being provided with spaced walls, the walls of said compression member and the walls for a portion of the length of said upper part being spaced apart at a greater distance than the walls of said lower part, reinforcing ribs between the walls of said compression member, and spaced walls connecting the walls of said upper and lower parts, said walls originating adjacent the intersection of said members and converging from the walls of said upper part to merge with the walls of said lower part.

50 11. In a side frame, the combination of tension and compression members terminating in an integral journal box receiving portion, said portion being provided with upper and lower parts formed as substantial continuations of said members, said parts and said compression member being provided with spaced walls, the walls of said compression member and the walls for a portion of the length of said upper part being spaced apart at a greater distance than the walls of said lower part and the walls of said upper part for the remaining portion of their length being at a less distance apart, and spaced walls connecting the walls of said upper and lower parts, said walls originating adjacent the intersection of said members and converging from the walls of said upper part to merge with the walls of said lower part.

55 12. In a side frame, the combination of tension and compression members terminating in an integral journal box receiving portion, said portion being provided with upper and lower parts formed as substantial continuations of said members, said parts and said compression member being provided with spaced walls, the walls of said com-

pression member and the walls for a portion of the length of said upper part being spaced apart at a greater distance than the walls of said lower part and the walls of said upper part converging toward each other for the remaining portion of their length, and spaced walls connecting the walls of said upper and lower parts, said walls originating adjacent the intersection of said members and converging from the walls of said upper part to merge with the walls of said lower part.

13. In a side frame, the combination of tension and compression members terminating in an integral journal box receiving portion, said portion being provided with upper and lower parts formed as substantial continuations of said members, said parts and said compression member being provided with spaced walls, the walls of said compression member and the walls for a portion 15 of the length of said upper part being spaced apart at a greater distance than the walls of said lower part and the walls of said upper part for the remaining portion of their length being at a 20 less distance apart, reinforcing ribs between the walls of said compression member, and spaced walls connecting the walls of said upper and lower parts, said walls originating adjacent the intersection of said members and converging from the 25 walls of said upper part to merge with the walls 30 of said lower part.

14. In a side frame, the combination of tension and compression members terminating in an integral journal box receiving portion, said portion being provided with upper and lower parts formed
35 as substantial continuations of said members, said parts and said compression member being provided with spaced walls, the walls of said compression member and the walls for a portion of the length of said upper part being spaced apart
40 at a greater distance than the walls of said lower part and the walls of said upper part converging toward each other for the remaining portion of their length, reinforcing ribs between the walls of said compression member, and spaced walls
45 connecting the walls of said upper and lower parts, said walls originating adjacent the intersection of said members and converging from the walls of said upper part to merge with the walls of said lower part.

50 15. In a side frame, the combination of tension and compression members terminating in an integral journal box receiving portion, said portion being provided with upper and lower parts formed as substantial continuations of said members,
55 said parts and members being provided with spaced walls and connecting webs, the walls of said compression members and the walls for a portion of the length of said upper part being spaced apart at a greater distance than the walls
60 of said lower part, and spaced walls connecting the walls of said upper and lower parts, said walls originating adjacent the intersection of said members and converging from the walls of said upper part to merge with the walls of said lower
65 part, the web of said tension member being of integral and continuous construction and of tapering thickness.

16. In a side frame, the combination of tension and compression members terminating in an integral journal box receiving portion, said portion being provided with upper and lower parts formed as substantial continuations of said members, said parts and members being provided with spaced walls and connecting webs, the walls of said compression members and the walls for a

portion of the length of said upper part being spaced apart at a greater distance than the walls of said lower part, and spaced walls connecting the walls of said upper and lower parts, said walls originating adjacent the intersection of said members and converging from the walls of said upper part to merge with the walls of said lower part, the web of said tension member being of integral and continuous construction and of tapering thickness, the greatest thickness being adjacent one corner of the associated journal box. 5 10

17. In a side frame, the combination of tension and compression members terminating in an integral journal box receiving portion, said portion being provided with upper and lower parts formed as substantial continuations of said members, said parts and members being provided with spaced walls and connecting webs, the walls of said compression members and the walls for a portion of the length of said upper part being spaced apart at a greater distance than the walls of said lower part, reinforcing ribs between the walls of said compression member, and spaced walls connecting the walls of said upper and lower parts, said walls originating adjacent the intersection of said members and converging from the walls of said upper part to merge with the walls of said lower part, the web of said tension member being of integral and continuous construction and of tapering thickness.

30
18. In a side frame, the combination of tension and compression members terminating in an integral journal box receiving portion, said portion being provided with upper and lower parts formed as substantial continuations of said members, said parts and members being provided with spaced walls and connecting webs, the walls of said compression members and the walls for a portion of the length of said upper part being spaced apart at a greater distance than the walls 40 of said lower part and the walls of said upper part for the remaining portion of their length being at a less distance apart, and spaced walls connecting the walls of said upper and lower parts, said walls originating adjacent the intersection of said members and converging from the walls of said upper part to merge with the walls 45 of said lower part, the web of said tension member being of integral and continuous construction and of tapering thickness. 50

19. In a side frame, the combination of tension and compression members terminating in an integral journal box receiving portion, said portion being provided with upper and lower parts formed as substantial continuations of said members, said parts and members being provided with spaced walls and connecting webs, the walls of said compression members and the walls for a portion of the length of said upper part being spaced apart at a greater distance than the walls of said lower part and the walls of said upper part converging toward each other for the remaining portion of their length, and spaced walls connecting the walls of said upper and lower parts, said walls originating adjacent the intersection of said members and converging from the walls of said upper part to merge with the walls of said lower part, the web of said tension member being of integral and continuous construction and of tapering thickness. 55 60 65 70

20. In a side frame, the combination of tension and compression members terminating in an integral journal box receiving portion, said portion being provided with upper and lower parts formed as substantial continuations of said mem- 70

bers, said parts and members being provided with spaced walls and connecting webs, the walls of said compression members and the walls for a portion of the length of said upper part being spaced apart at a greater distance than the 5 walls of said lower part and the walls of said upper part for the remaining portion of their length being at a less distance apart, reinforcing ribs between the walls of said compression member, and spaced walls connecting the walls of said upper and lower parts, said walls originating adjacent the intersection of said members and converging from the walls of said upper part to merge with the walls of said lower part, the web 10 of said tension member being of integral and continuous construction and of tapering thickness.

21. In a side frame, the combination of tension and compression members terminating in an integral journal box receiving portion, said portion being provided with upper and lower parts 20 formed as substantial continuations of said members, said parts and members being provided with spaced walls and connecting webs, the walls of said compression members and the walls for a portion of the length of said upper part being spaced apart at a greater distance than the walls 25 of said lower part and the walls of said upper part converging toward each other for the remaining portion of their length, reinforcing ribs between the walls of said compression member, and spaced walls connecting the walls of said upper and lower parts, said walls originating adjacent the intersection of said members and converging from the walls of said upper part to merge with the walls of said lower part, the web 30 of said tension member being of integral and continuous construction and of tapering thickness.

22. In a side frame, the combination of tension and compression members terminating in an integral journal box receiving portion, said portion being provided with upper and lower parts formed 40 as substantial continuations of said members, said parts and members being provided with spaced walls and connecting webs, the walls of said compression members and the walls for a portion of the length of said upper part being spaced apart at a greater distance than the walls 45 of said lower part, reinforcing ribs between the walls of said compression member, and spaced 50 walls connecting the walls of said upper and lower parts, said walls originating adjacent the intersection of said members and converging from the walls of said upper part to merge with the walls of said lower part, the web of said tension member being of integral and continuous construction and of tapering thickness, the greatest thickness being adjacent one corner of the associated journal box.

23. In a side frame, the combination of tension and compression members terminating in an integral journal box receiving portion, said portion being provided with upper and lower parts formed 60 as substantial continuations of said members, said parts and members being provided with spaced walls and connecting webs, the walls of said compression members and the walls for a portion of the length of said upper part being spaced apart at a greater distance than the walls 65 of said lower part and the walls of said upper part for the remaining portion of their length being at a less distance apart, and spaced walls connecting the walls of said upper and lower parts, said walls originating adjacent the intersection of 70 said members and converging from the walls of said upper part to merge with the walls of said

lower part, the web of said tension member being of integral and continuous construction and of tapering thickness, the greatest thickness being adjacent one corner of the associated journal box.

24. In a side frame, the combination of tension and compression members terminating in an integral journal box receiving portion, said portion being provided with upper and lower parts formed 10 as substantial continuations of said members, 15 said parts and members being provided with spaced walls and connecting webs, the walls of said compression members and the walls for a portion of the length of said upper part being spaced apart at a greater distance than the walls 20 of said lower part and the walls of said upper part converging toward each other for the remaining portion of their length, and spaced walls connecting the walls of said upper and lower parts, said walls originating adjacent the intersection of said members and converging from the walls of said upper part to merge with the walls of said lower part, the web of said tension member being of integral and continuous construction and of tapering thickness, the greatest thickness being adjacent one corner of the associated journal box.

25. In a side frame, the combination of tension and compression members terminating in an integral journal box receiving portion, said portion 30 being provided with upper and lower parts formed as substantial continuations of said members, said parts and members being provided with spaced walls and connecting webs, the walls of said compression members and the walls for a 35 portion of the length of said upper part being spaced apart at a greater distance than the walls of said lower part and the walls of said upper part for the remaining portion of their length being at a less distance apart, reinforcing ribs 40 between the walls of said compression member, and spaced walls connecting the walls of said upper and lower parts, said walls originating adjacent the intersection of said members and converging from the walls of said upper part to merge 45 with the walls of said lower part, the web of said tension member being of integral and continuous construction and of tapering thickness, the greatest thickness being adjacent one corner of the associated journal box.

26. In a side frame, the combination of tension and compression members terminating in an integral journal box receiving portion, said portion being provided with upper and lower parts formed 50 as substantial continuations of said members, 55 said parts and members being provided with spaced walls and connecting webs, the walls of said compression members and the walls for a portion of the length of said upper part being spaced apart at a greater distance than the walls 60 of said lower part and the walls of said upper part converging toward each other for the remaining portion of their length, reinforcing ribs between the walls of said compression member, and spaced walls connecting the walls of said 65 upper and lower parts, said walls originating adjacent the intersection of said members and converging from the walls of said upper part to merge with the walls of said lower part, the web of said tension member being of integral and 70 continuous construction and of tapering thickness, the greatest thickness being adjacent one corner of the associated journal box.
